UNITED STATES PATENT OFFICE

KATHERINE GINNANE, OF BROOKLYN, NEW YORK, ASSIGNOR TO GOTHAM SILK HOSIERY CO., INC., OF NEW YORK, N. Y., A CORPORATION OF DELAWARE

STOCKING

Application filed November 1, 1926. Serial No. 145,437.

This invention relates to an improved full-fashioned stocking and has for its object the production of a neat, attractive and graceful well fitting stocking wherein the fashion marks and lines of knitted stitches are so arranged as to give an improved shaping formation to the stocking whereby the fullness of the upper or calf portion of the leg is accentuated, while in the lower or ankle portion slenderness and the graceful curvatures are rendered more pronounced.

Other objects will appear hereinafter, and I attain these objects by the illustrative construction disclosed in the accompanying drawing in which:

Figure 1 is a view of a stocking which shows my invention applied thereto.

Fig. 2 is an enlarged view of a portion of the shaping formation at the lower end thereof, and

Fig. 3 is an enlarged view showing the lines of stitches and the formation of the line of fashion marks.

In the art of manufacturing full fashioned hosiery the action of the narrowing needles which fashion the fabric to the exact shape is such that they dip down into the fabric and pick up a predetermined number of outside loops and carry them towards the center line of the fabric and place them back into operation, that is, outside loops are replaced on needles closer to the center of the needle bank, so that the entire needles knitting are a lesser number. This operation forms the characteristic "fashion marks" of the full fashioned stocking.

In the fashioning process as heretofore practiced the same number of loops are always carried towards the center of the stocking and therefore the fashion marks appear in a line parallel with the selvage edge of the stocking. The stitch lines between the fashion marks and the selvage edge form substantially straight parallel lines. The arrangement of the lines of fashion marks and the stitch lines between them and the selvage edge produces the known rectangular panel effect in the finished stocking which is generally unsightly in appearance and fails in

neatness or in giving a trim fit to the stocking when worn.

In the present invention the objections noted above are obviated and a neat fit is produced by so operating the narrowing needles that the fashion marks converge inwardly and downwardly from the point where the fashioning in the knitted fabric commences, to a point near and adjacent to the selvage edge, instead of running parallel to said edge as heretofore. The stitch lines between the fashion marks and the selvage edge are parallel to each other and to the selvage edge of the stocking fabric, but by reason of the periodically repeated dipping operation of the narrowing needles and the constant decrease in the number of needles remaining active, there will be an ending of one of the stitch rows at the successive fashion marks thus produced in a converging line on inner side of the selvage edges. It is understood that the seam in the finished stocking is formed by stitching together the selvage edges of the stocking fabric. The arrangement then produced by the converging lines of fashion marks and the lines of stitches enclosed by said lines meeting at an angle with the stocking seam, produces an angular formation in the rear portion of the stocking, the point of which terminates preferably at, or just above, the ankle region of the wearer of said stocking. This angular formation will be known herein as the "shaping formation." This shaping formation produces a superior fitting stocking and has a most desirable optical effect in causing the ankle to look small and slender while the shape of the calf of the leg is apparently accentuated.

While lines of fashioning marks 11, 11 appear in the drawing as slightly curved they may be made straight, or greatly curved or a combination of straight or curved, if desired. Moreover the angle 12 formed by the lines of fashion marks, may be greater or less than that shown herewith for the purpose of illustration. In all cases, however, the angle should be small so as to give the desired effect.

The angular "shaping formation" 10 is formed by the parallel lines of stitches or

wales 13, said wales in general, run parallel to each other and to the selvage edges shown as seam 14 which is formed by joining said selvage edges. These stitch lines join the 5 lines of fashioning marks 11 at the different fashioning marks 15, which in effect unite two of the parallel lines of stitches with the rows of outer line of stitches or wales 17 as is best shown in Fig. 2. The location of these 10 points will of course, determine the contour or extent of the angular shaping formation, and this difference is caused by varying the number of the stitches between the different fashioning points as is readily understood by 15 those versed in the art.

In one form of construction the wales 17 of the stocking outside the shaping formation, are in general, parallel with the line of fashioning marks. They are also parallel 20 with each other and with the selvage edge above the shaping formation in the ankle region 16 of the finished stocking. These lines may extend to and in part form the reinforced heel piece 18 and heel 19 and constitute 25 the vertical lines of stitches of the stocking body with the apparent inset of the shaping formation to produce the optical effect and the desired neat fit.

The herein disclosed shaping formation 30 may be produced in the stocking body in any desired manner and preferably by knitting in the following manner.

It has been noted above that in the usual method of narrowing full fashioned stockings 35 the rows of fashion marks caused by the narrowing run parallel with the seam of the stocking. In the present invention, the fashioning marks caused by the narrowing operation do not run parallel to the seam 40 but are inclined towards the same at any desired angle. Thus for example, if, in knitting the stocking fabric and at the beginning of fashioning there are thirty narrowing fingers in operation, this number is 45 decreased progressively so that the last fashioning point is closely adjacent the selvage edge and the fashioning marks 15 will be substantially straight as shown as lines 11. The angle of the lines 11, 11 with the selvage 50 edges (seam 14) depends upon the distance or number of stitches between successive fashioning marks. For example, if say five or six stitches are formed between successive fashioning marks a definite angle is 55 formed with the selvage edge. If a greater number of stitches is used, say 10, then the angle of the line of fashioning points with the selvage edge will be more acute.

By referring to the drawing it will be noted 60 that the vertical lines of stitches or wales 13 are, as stated above, substantially parallel with the selvage edges (seam 14 in the finished stocking) and are constantly decreasing at the fashioning marks. It will also be 65 noted that the wales 17 are in general par-

allel to each other and to the line of fashion points thereby giving the desired result, as stated above.

Having now described my invention, what I claim as new and useful, and desire to set 70 cure by Letters Patent is:

1. In a full fashioned stocking having a seam, an angular shaping conformation composed of wales on either side of the stocking seam, said wales ending at merging points to 75 form substantially straight lines of fashioning marks disposed at an angle to each other and diverging from said seam.

2. A stocking having a seam and a shaping formation bordered by fashioning marks 80 to outline the enlarged portion of said stocking, said formation narrowing to a point above the heel and shaping wales in parallel relation with each other and with the lines of fashioning marks. 85

3. In a full fashioned stocking having selvage edges united into a seam, a shaping formation through which said seam runs, said shaping formation composed of wales parallel to said seam, and lines of fashioning 90 marks in which said wales merge, said lines of fashioning marks disposed at an angle to the seam. 95

4. A full fashioned hosiery blank having selvage edges and wales parallel to said selvage edges, said wales ending in merging points constantly closer to said selvage edges so that the merging points form lines of fashioning marks disposed at an angle to the 100 selvage edges. 105

5. As an article of manufacture, a full fashioned stocking having a finishing seam and shaping formations on either side of said seam, said formations formed by parallel wales of varying length and merged into lines 105 of fashioning points which diverge from either side of said finishing seam. 110

6. As an article of manufacture, a full fashioned stocking having a shaping formation divided by a seam, said formation formed by wales parallel with said seam and meeting in a line of fashioning marks at different levels, said line of fashioning marks forming an angle with the seam. 115

In testimony whereof I have hereunto set 115 my hand on this 29th day of October, A. D., 1926.

KATHERINE GINNANE.
